STOCK QUOTATION PROJECTION MACHINE

August D. Eitzen, Rockville Centre, N. Y., assignor to News Projection Corporation, New York, N. Y., a corporation of New York

Application May 1, 1937, Serial No. 140,201

3 Claims. (Cl. 88—24)

This invention relates to stock quotation projection machines in general.

Among the objects of the present invention, it is aimed to provide an improved stock quotation projection machine in which the tape can with facility be fed across a light aperture or other support in a smooth and proper condition for projection by a device interposed between the ticker and the light aperture and without any further controlling means.

It is still another object of the present invention to provide an improved mechanism for treating the tape whereby the same may be fed across a light aperture and the vibrations ironed out of the same by one and the same device interposed between the ticker and the light aperture.

These and other features, capabilities and advantages of the invention will appear from the subjoined detail description of specific embodiments thereof illustrated in the accompanying drawings in which:

Figure 1 is a front elevation partly broken away and partly in section of one embodiment of the present invention;

Fig. 2 is a fragmental plan partly in section of the embodiment illustrated in Fig. 1;

Fig. 3 is an enlarged fragmental section on the line 3—3 of Fig. 1;

Fig. 4 is an enlarged fragmental section on the line 4—4 of Fig. 1; and

Fig. 5 is an enlarged fragmental section of a part of another embodiment.

In the embodiment shown in Fig. 1, the tape 1 as it leaves the ticker 2, preferably of the high speed type in which the normal feed has been disabled, is first engaged by the tape advancing roller 3 drivingly connected to the motor 4 by means including the belt 5, the tape 1 being pressed into driving engagement with the roller 3 by the pressure roller or spring pressed idler 6.

In the present instance, see Fig. 4, the tape advancing roller 3 has a creasing rib 7 cooperating with the groove 8 in the idler 6 to form an upwardly extending rib or crease 9 in the middle 45 of the tape 1 along the narrow extended area between the letters 10 constituting the stock symbols and the numbers 11 constituting the quoted prices. This creasing rib 9 will so stiffen or rigidify the tape 1 that it can with facility be engaged between the ticker 2 and the light aperture now to be described not only to iron out the vibrations transmitted to the tape 1 by the ticker 2 but also effectively to advance the tape across the light aperture without any guiding means or advancing assistance.

In the present instance, however, there are provided the lateral guiding means such as the shoulders 12 and 13 formed by the top walls 14 and 15 of the extension 16 of the lamp housing 17. The tape 1 here rides directly on the upper plane supporting surface of the condensing lens 18 mounted in the extension 16 adjacent the upper walls 14 and 15 and adjacent the front wall 19. Preferably as here shown, there is secured a transparent sheet, such as the glass plate 20 to 10 the upper faces of the wall members 14 and 15 so that this glass plate 20, cut condenser 18 and wall members 14 and 15 will cooperate to form a guiding pocket for the tape 1 whereby the tape will be guided in a smooth condition while crossing the light aperture formed by the condenser 18 between the walls 14 and 15. As the tape 1 after having been marked by the ticker 2, appears at the light aperture on the condenser 18, image impressed light beams are formed by the light 20 passing up through the condenser 18 and tape 1, which light beams are intercepted by the objective lens unit in the casing 21 supported in position by the bracket 22 extending upwardly from the extension 16, which objective lens unit 25 in turn directs the image impressed light beams onto the mirror or reflector 23 which directs them onto the mirror or reflector 24, which in turn directs them onto the rear of the projection screen 25 to be legible on the front of the screen 25. 30

Preferably as shown in Fig. 1, the screen 25 is provided with an opaque strip 26 to align with the projection of the rib 9 so as to conceal the same when desired.

After leaving the condenser 18, the tape is 35 preferably passed to the extension 27 which extends into the cage 28 preferably composed of wire screening or other suitable foraminous material into which there extends in the embodiment shown in Fig. 1, the jet or flame from the 40 burner nozzle 29 communicating with the lower end of the cage 28 and extending upwardly from the oil burner 30 connected to the side of the extension 16. The extension 27, cage 28 and upper end of the nozzle 29 are preferably disposed 45 in the casing 31 which is provided with air inlets 32 at the bottom thereof in the interest of combustion and a screened opening 33 at the upper end thereof in communication with the flue pipe 34 or the like. 50

With this burner arrangement, it is not necessary to use a rewind of any kind and the tape as it has served its usefulness is destroyed, the front feed and rib 9 of course cooperating with the burner to dispense with a rewind of any kind. 55

In the embodiment shown in Fig. 5, the tape 35 after it leaves the light aperture passes to the extension 36 extending into the housing 37 having openings 38 at the lower end thereof in the interest of combustion and a wire 39 constituting an electric heater unit connected to the contacts 40 and 41 connected to the conductors of a suitable source of electric current at the upper end of the housing 37. Similarly there is provided a screened opening 42 in communication with a flue pipe 43 or the like.

In the embodiment of Fig. 1, the cage 28 is preferably cylindrical as shown in Fig. 2 and anchored in place by the spring fingers 44 extending from the side of the extension 16. Furthermore the housing 31 is preferably provided with a hinged closure 45 which may be opened to afford access to the cage 28.

The cage 46 of the embodiment illustrated in Fig. 5 preferably is also anchored in place by spring fingers, such as the spring fingers 44 of Fig. 1, and the door 47 there provided is also provided to afford access to the cage 46.

It is obvious that various changes and modifications may be made to the details of construction without departing from the general spirit of the invention as set forth in the appended claims.

I claim:

1. The combination of a ticker, an inspection area having a plane supporting surface, means interposed between said ticker and said inspection area for advancing the tape from said ticker to and across the supporting surface of said inspection area, said advancing means including a driven roller and a pressure roller for maintaining the tape in driving engagement with said

driven roller, and cooperating rib forming die faces on said driven and pressure rollers for forming a longitudinally extending stiffening rib in the tape to facilitate the steady advancement of the tape across said inspection area in intimate engagement with said supporting surface.

2. The combination of a ticker, an inspection area having a plane supporting surface, means interposed between said ticker and said inspection area for advancing the tape from said ticker to and across the supporting surface of said inspection area, said advancing means including a driven roller and a pressure roller for maintaining the tape in driving engagement with said driven roller, an annular rib forming projection on said driven roller, and an annular depression in said pressure roller registering with said projection on said driven roller for forming a longitudinally extending stiffening rib in the tape to facilitate the steady advancement of the tape across said inspection area in intimate engagement with said supporting surface.

3. The combination of a ticker, a light aperture pocket formed by the plane surface of a condensing lens, a glass plate above said condensing lens, and lateral walls on the side, means interposed between said ticker and said pocket for advancing a tape from said ticker to and through said pocket, and means for forming a longitudinally extending rib in the tape for stiffening it to facilitate its movement through said pocket in intimate engagement with said plane surface, the width of the pocket conforming to the width of the tape and the height of the pocket conforming to the height of the rib on the tape.

AUGUST D. EITZEN.
